INVENTOR
BY Victor J. Evans

ATTORNEY

UNITED STATES PATENT OFFICE.

EUGENE N. DWIGHT, OF WILLOW GROVE, PENNSYLVANIA.

CARBON BURNER.

Application filed May 29, 1925. Serial No. 33,766.

This invention relates to a carbon burner or mixer attachment for furnaces, and an object of the invention is to provide a burner structure for attachment to furnaces or the like, which will mix oxygen or air with the carbon monoxide gas which forms within the fire-box of the furnace, and renders the carbon monoxide gas inflammable and causes it to ignite and burn in the furnace, thereby deriving the maximum amount of heat from the fuel used.

Another object of this invention is to provide a burner as specified, which includes a frustro-pyramidal body having a wedge-shaped inlet opening at its large end and provided with a plurality of baffles arranged staggeredly to cause a sinuous movement to the air or oxygen as it passes through the burner to insure preheating of the oxygen or air prior to its admission into the furnace and also to provide baffles, certain of which are inclined from their center towards each edge for dividing the entering air or oxygen to cause it to travel in two directions through the preheater or burner structure.

Another object of the invention is to provide a burner as specified, which is simple in construction, requires no adjustments, and one which may be easily and quickly as well as inexpensively installed.

Other objects of the invention will appear in the following detail description, and in the accompanying drawings wherein:

Figure 1 is a side elevation of the improved burner.

Figure 2 is a longitudinal section through the burner.

Figure 3 is an end elevation of the inlet end of the burner.

Figure 4 is an end elevation of the outlet end of the burner.

Referring more particularly to the drawings, the improved carbon burner includes a substantially frustro-pyramidal body 1 which has three of its sides cast integrally and the last or fourth side 2 attached thereto by means of a toe and heel joint 3, and lugs 4. The lugs 4 are formed upon the edges of the sides 5 against which the side 2 rests. The inlet end 6 of the burner structure is provided with a wedge-shaped inlet opening 7 at its center, through which opening the air enters the body 1. As the air enters the body 1, it engages against the baffle 8 which inclines towards the inlet end 6 from

each edge of the baffle toward its center as clearly shown in Fig. 2 of the drawings, for bisecting the inflowing air and directing it in opposite directions transversely through the body. The air passes about the ends of the baffle 8 and is deflected inwardly towards the longitudinal axis of the body along the surfaces of the baffles 9, passing through the space between the facing ends of the baffles 9 and against the baffle 10, which again bisects the stream of air and directs it transversely along the sides and then about the ends of the baffle 10. This sinuous and bisecting movement of the air is kept up throughout the entire length of the body 1 by means of the various baffles 8, 9, 10 and 11, and the central short baffles 12 which are near the outlet end. The baffles 12 incline from their outer edges inwardly towards the outlet end or in the opposite direction to the inclining of the baffles 8 and 10. Outlet is had from the body 1 through the openings 13 in the plate 14 and the openings 15 in the outer end 16.

The inlet opening 7 is positioned at the center of the inlet end 6 and perpendicular to prevent any cooling effect and admits the air or oxygen inwardly to the deflecting plate 8 which bisects the flow as above specified, and causes the incoming oxygen or air to enter the various stages within the body 1 during which time the air is retarded and deflected so as to cause thorough dissemination and expansion for absorbing heat so that as it passes out of the body it is superheated and the deflector is neutralized with the deflector within the furnace so that it will mix thoroughly and efficiently with any carbon monoxide gas within the furnace, changing the gas to carbon dioxide and causing its instantaneous ignition and the releasing of the heat units therefrom.

The inlet end 6 has bolt receiving bosses 17 which are adapted to receive suitable bolts for attaching the burner to a furnace and if it is so desired, a sheet of asbestos as indicated at 18, may be placed against the outer surface of the inlet end 6 and held in place by the bolts used for attaching the burner to a furnace.

Adjustments are not provided for regulating the inlet of air as the flow of the air or oxygen through the burner is automatically regulated by the regular approved type of draft dampers (not shown) used on

the furnace in connection with which the burner is used, and the inlet opening 7 is of sufficient size for maximum inlet of air.

From the foregoing description taken in connection with the accompanying drawings, it will be apparent that a burner has been provided which is simple in construction, durable, may be cheaply manufactured, and installed, and one which will result in the thorough and complete utilization of the heat producing proclivities of the fuel used.

It is, of course, to be understood, that the invention may be constructed in various other manners and the parts associated in different relations, and therefore, I do not desire to be limited in any manner, except as set forth in the claim hereunto appended.

What I claim is:—

20 A carbon monoxide burner comprising a rectangular body tapering from its inlet end to the outlet end thereof, said body provided in the face of its inlet end with a centrally and vertically disposed slot having 25 inclined side edges tapering towards the up-

per end with the ends of said slot extended adjacent the outer wall of said body, a plurality of relatively small staggered outlet apertures provided in the outlet end of said body, a plurality of integrally formed vertical partitions equally spaced within said body, said partitions laterally extended from opposite sides of said body and divided centrally to provide a passage there between, a plurality of integrally formed 30 baffle plates disposed intermediate said partitions with the ends thereof terminating adjacent the said opposite sides to provide a second passage on each side of said first named passage, said baffle plates 40 inclined from their outer ends to the centers thereof to bisect an incoming stream of air towards the free ends of said baffle plates and through said first named passage to provide a sinuous path through said body 45 substantially as described.

In testimony whereof I affix my signature.

EUGENE N. DWIGHT.
